To all whom it may concern:

Be it known that I, Mathew F. Kritchever, a citizen of the United States, residing at Wilmette, county of Cook and State of Illinois, have invented a new, original, and ornamental Design for Ash Container, of which the following is a specification, reference being had to the accompanying drawing, forming a part thereof, in which:

Fig. 1 is a perspective view of the ash container, showing my new design,

Fig. 2 is a plan view,

Fig. 3 is a side elevational view,

Fig. 4 is a front elevational view, and

Fig. 5 is a rear elevational view.

I claim:

The ornamental design for an ash container, as shown.
